DIRECTORY OR, INDEX BOARD

Filed June 28, 1922

2 sheets-sheet 2

UNITED STATES PATENT OFFICE.

CHARLES F. REUSCHLEIN, OF HUNTINGTON, WEST VIRGINIA.

DIRECTORY OR INDEX BOARD.

Application filed June 28, 1922. Serial No. 571,339.

To all whom it may concern:

Be it known that I, CHARLES F. REUSCHLEIN, a citizen of the United States, residing at Huntington, in the county of Cabell 5 and State of West Virginia, have invented certain new and useful Improvements in a Directory or Index Board; and I do hereby declare the following to be a full, clear, and exact description of the invention, such as 10 will enable others skilled in the art to which it appertains to make and use the same.

This invention relates to a directory or index board.

It is aimed to provide in an article of this 15 type wherein the display cards or panels are movable over others for insertion and removal, means to enable said insertion or removal without disturbing the arrangement or otherwise interfering with other 20 display cards or panels of the directory or board.

Another object is to provide in such an apparatus, card or panel retainers or holders provided with lugs to limit insertion of 25 the cards or panels and function dually to deflect an adjacent cardboard panel outwardly as it is removed.

It is further aimed to provide a construction accomplishing the result mentioned 30 which is simple and inexpensive, and capable of embodiment in a holder consisting of a single blank or piece.

A still further object is to provide a novel construction of index studs and an attaching means, particularly utilizing pin and slot connections in association with springs to maintain the studs in display 35 positions.

Additional objects and advantages will 40 become apparent from a consideration of the description following taken in connection with accompanying drawings illustrating one practical embodiment.

In said drawings:—

45 Figure 1 is a front elevation fragmentarily illustrating a directory or index board constructed in accordance with my invention;

Figure 2 is a longitudinal sectional view on the line 2—2 of Figure 1, and showing 50 a display card or panel in the act of removal;

Figure 3 is a cross sectional view on the line 3—3 of Figure 1;

Figure 4 is a cross sectional view on the 55 line 4—4 of Figure 1;

Figure 5 is a detail perspective view of one of the panel retainers or holders alone;

Figure 6 is a detail perspective view of one of the index studs looking toward the rear thereof and partly broken away; 60

Figure 7 is a front elevation fragmentarily illustrating a modified form of the invention with the index studs removed;

Figure 8 is a cross sectional view on the line 8—8 of Figure 7; 65

Figure 9 is a detail perspective view of a modified form of index stud looking toward the rear thereof, and

Figure 10 is an enlarged sectional view also of the modified form of the index stud. 70

Like reference characters designate like or similar parts in the different views.

The illustration is to be taken generally and broadly as a sign and one specific example being its use as a directory in an 75 office or other building.

In reducing the invention to practice, a base or back board is provided at 10 which may be made of wood, metal or another suitable material. The base 10 may be rectangular for example and bordered by a frame 11 at its sides and ends, and secured thereto in any appropriate manner or formed integral therewith, as preferred. 80

Retainers or holders 12 for removable 85 cards or panels 13, to contain directions or display matter cover the board 10 at the display face thereof in any desired numbers and arrangements, preferably in vertical rows and in horizontal rows as shown. 90 The panels 13 are usually of a flexible nature and of pasteboard.

The holders or retainers 12 may each be made in a single piece or blank of sheet metal and soldered, nailed or otherwise secured to the board 10. Each holder at each longitudinal edge thereof is preferably bent over as shown to provide retaining flanges 14 for the panels 13 and between which flanges and the boards the panels are adapted to slide longitudinally of the holders. 95

Struck out from each holder or retainer 12 in the same direction as the flanges is a lug 15. As the panels 13 are insertable into the holders by sliding movement toward the right of Figure 1, the panels will abut the lugs 15 as shown in Figure 1 and Figure 2, thus limiting their extent of insertion and insuring proper positioning thereof. At the same time when the panels are re- 105

2
moved, say the panels of the first vertical row, and as illustrated in Figure 2, said panels will engage the lugs 15 which will deflect the same at the left hand end outwardly, so that they will not engage or disturb the panels to the left of them and so that they may be readily engaged by the fingers to facilitate removal. The initial movement for removing the panels 13 may 10 be imparted by engagement of the index or other finger with the right hand end of the panels or otherwise as will be obvious. Thus it will be seen that the lugs 15 function dually, to limit insertion of the panels 15 and also to deflect adjacent panels out of engagement or contact with the panels for which they serve as abutments or stops.

It will be realized that when desired the flanges 14 and lugs 15 may be provided directly on board 10, when the latter is made of metal, or all holders or retainers made in a single piece so as to avoid the necessity of using separate panels 12.

The marginal frame 11 preferably has its 25 display or front wall arcuate or rounded as at 16, although it may be of any shape preferred, and its back or base wall plane or flat as at 17. As a result, this frame is hollow as shown. In the wall 16 at one side 30 of the directory, preferably the left hand side, a plurality of key hole slots 18 are provided therethrough and directly in the rear thereof, a plurality of leaves 19 are struck inwardly from the walls 17. The walls 16 and 17 are 35 preferably of sheet metal and accordingly the leaves 19 will be resilient or springs.

Index studs having display plates as at 20 which display the letters of the alphabet by way of example, are employed. Attaching pins 21 extend rearwardly from the plates 20 and terminate in heads 22. Pins 21 and heads 22 may be integral with the plates 20 if desired and as shown.

As the heads 22 are of such size that they 45 may be inserted into and withdrawn from the key hole slots, the index studs may be readily applied to or removed from the slots 18. When the heads 22 have been passed through the slots 18 and disposed within the 50 recess of the frame, said heads may be lowered so as to dispose the pins 21 in the smaller portions of the slots 18 with the heads 22 overlapping the inner surface of the wall 16 and in engagement with the leaves 55 19, the latter serving to frictionally bind against the heads 22 and the heads 22 against the walls 16, whereby plates 20 may be releasably held in place, and particularly so that they cannot accidentally rotate. As they 60 cannot accidentally rotate, the plates 20 will be maintained with the letters of the alphabet or other display matter in proper reading position.

The feature of the index composed of the 65 separable plates 20 enables the plates to be

selectively applied to slots 18 so that the number of horizontal rows of panels for the different letters may be varied.

Referring to that form of the invention shown in Figures 7 and 10 of the drawings, 70 it will be noted that the same comprises a base or board 21 provided with the retaining flanges 22 and 23 which are stamped or pressed from the base 21 and the key hole slots 24 are also provided for the reception 75 of the index studs 25. This form of the invention while it does not have the same artistic appearance as does the form of invention illustrated in the other figures of the drawings, still may be much more 80 cheaply manufactured and sold. It will be appreciated that the base 21 may have the flanges 22 and 23, the key hole slots 24, and the lugs 15 stamped therefrom in one operation. To cooperate with the modified form of base 21 I have provided the button 25 from the back wall of which is stamped or pressed the attaching stud 26 including the oppositely disposed arms 27. The button has its edge bent to provide a 85 flange 28 between which and the back of the button a display plate may be located. The index buttons may be inserted through the round part of the key hole slot 24 and dropped into the elongated portion thereof, 90 with its laterally extending arm 27 engaging the rear of the base 21, whereby the button will be held against accidental displacement.

As merely preferred embodiments of the 100 invention have been illustrated and described, it is to be understood that changes in the details may be resorted to provided they fall within the spirit and scope of the invention.

Having thus described the invention, 105 what I claim is:—

1. In a sign, first and second walls, the first mentioned wall having a slot therethrough, an index member provided with 110 a pin to enter said slot, a securing head on said pin, and resilient means extending from the other wall and engaging said head to maintain the index member against displacement.

2. In a sign, said sign having a plurality of slots, index members selectively applicable to said slots for the purpose specified, and resilient means to coact with the index members to retain them against displacement.

3. In a sign, a plurality of display panels, means removably receiving said panels, a plurality of slots adjacent one edge of said sign, one of said slots being in alignment with each of said panels, index studs selectively applicable to said slots, and resilient means engaging said studs to prevent their accidental displacement.

4. In a sign provided with a slot, an in- 130

dex member having a shank to engage in said slots and resilient means to engage the shank to maintain the index member in active position.

- 5 5. A sign comprising a body of metal having longitudinal spaced parallel flanges extending from one face thereof, said flanges being spaced apart and in opposed relation to form pairs for receiving panels, 10 lugs inclining outward from said body and between pairs of flanges and adjacent the ends thereof, said lugs forming stops for panels received between one pair of opposed flanges and deflectors for panels received 15 by an adjacent pair of flanges, slots adjacent one edge of said body, one of said slots being in alignment with each pair of said flanges, and index studs to be selectively received by said slots.
- 20 6. A sign comprising a body of metal having longitudinal spaced parallel flanges

extending from one face thereof, said flanges being spaced apart and in opposed relation to form pairs for receiving panels, lugs inclining outward from said body and 25 between pairs of flanges and adjacent the ends thereof, said lugs forming stops for panels received between one pair of opposed flanges and deflectors for said panels received by an adjacent pair of flanges, 30 slots adjacent one edge of said body, one of said slots being in alignment with each pair of said flanges, studs selectively received by said slots, and resilient means to hold said studs against displacement. 35

In testimony whereof I affix my signature in presence of two witnesses.

CHARLES F. REUSCHLEIN.
